**SYSTEM AND METHOD FOR DISPERSING
PARTICLES WITHIN A TOY OR
ORNAMENT AND TOY OR ORNAMENT
INCORPORATING THE SAME**

FIELD

The present invention is generally related to toys or ornaments in which decorative particles are dispersed to simulate falling snow.

BACKGROUND

A snow globe is a transparent sphere, traditionally made of glass, enclosing a miniaturized scene of some sort, often together with a model of a town, landscape or figure. The sphere also encloses the water in the globe; the water serves as the medium through which the "snow" falls. To activate the snow, the globe is shaken to churn up the white particles. The globe is then placed back in its position and the flakes fall slowly through the water. Snow globes sometimes have a built-in music box that plays a song. Some snow globes have a design around the outer base for decoration. Snow globes are often used as a collectible item.

Known variations on the water-filled globe include snow lanterns that use forced-air to disperse the snow. These have a base with a blower, forcing air which carries polystyrene pellets from the bottom and through a tube to the top of the lantern, where they are blown out and fall around the scene. At least the sides of the lantern may be made of transparent material, such as, for example, transparent vinyl or glass. These lanterns are typically large decorations for the front yard and may be lighted internally with incandescent light bulbs.

Although the blower tube openings in conventional snow lanterns are typically hidden (for example, behind or within a Christmas tree model), the snow is seen by viewers as originating at specific points at the top of the lantern that correspond to the tube openings. This results in an unrealistic simulation of falling snow, which of course in real life does not originate from specific points in the sky but instead falls evenly across and around a scene.

Accordingly, there is a need for an improved design for a snow lantern that more realistically simulates falling snow.

SUMMARY

To address the above, the present disclosure is generally related to an improved snow lantern in which particles simulating snow are distributed evenly across a screen so that the particles fall in a more realistic manner over a scene within the lantern.

A snow lantern according to an exemplary embodiment of the present invention comprises: a display portion comprising a top opening; and a screen disposed over the top opening of the display portion, the screen comprising a plurality of screen openings through which pass particles for the simulation of falling snow within the display portion.

In an exemplary embodiment, the snow lantern further comprises two or more first tubes through with the particles are blown upwards through the display portion and over a top surface of the screen.

In an exemplary embodiment, the screen comprises two or more first tube connection openings in communication with the two or more first tubes.

2

In an exemplary embodiment, the two or more first tube connection openings comprise fittings that direct the particles over the top surface of the screen.

In an exemplary embodiment, the fittings direct the particles at an angle that is 80° to 100° relative to a longitudinal axis of the tubes.

In an exemplary embodiment, the fittings direct the particles at an angle that is 90° relative to a longitudinal axis of the tubes.

10 In an exemplary embodiment, the snow lantern further comprises two or more second tubes that house electrical wiring.

In an exemplary embodiment, the screen comprises two or more second tube connection openings in communication with the two or more second tubes.

In an exemplary embodiment, the display portion comprises a front portion and a back portion, and the screen is sloped downwardly from the back portion to the front portion.

20 In an exemplary embodiment, the screen is sloped at an angle of 10° to 30°.

In an exemplary embodiment, the screen is sloped at an angle of 20°.

In an exemplary embodiment, the screen has a profile that is convex relative to the top opening of the display portion.

A snow lantern according to an exemplary embodiment of the present invention comprises: a display portion comprising a top opening; a screen disposed over the top opening of the display portion, the screen comprising a plurality of screen openings; and two or more first tubes through with particles are blown upwards through the display portion and over a top surface of the screen so that the particles pass through the screen openings for the simulation of falling snow within the display portion, wherein: the two or more first tube connection openings comprise fittings that direct the particles over the top surface of the screen at an angle that is 80° to 100° relative to a longitudinal axis of the tubes, the display portion comprises a front portion and a back portion, and the screen is sloped downwardly at an angle of 10° to 30° from the back portion to the front portion, and the screen has a profile that is convex relative to the top opening of the display portion.

BRIEF DESCRIPTION OF THE DRAWINGS

Exemplary embodiments of the present disclosure will be described with references to the accompanying figures, wherein:

FIG. 1 is a perspective view of a snow lantern according to an exemplary embodiment of the present invention;

FIG. 2 is a top view of a snow lantern according to an exemplary embodiment of the present invention;

FIG. 3 is a front view of a snow lantern according to an exemplary embodiment of the present invention;

FIG. 4 is a back view of a snow lantern according to an exemplary embodiment of the present invention;

FIG. 5 is a side view of a snow lantern according to an exemplary embodiment of the present invention;

FIG. 6 is a top view of a display portion of a snow lantern according to an exemplary embodiment of the present invention;

FIG. 7 is a bottom view of a display portion of a snow lantern according to an exemplary embodiment of the present invention;

FIGS. 8A and 8B are side and top views, respectively, of tubes of a snow lantern according to an exemplary embodiment of the present invention;

FIG. 9 is an exploded view of a snow lantern according to an exemplary embodiment of the present invention;

FIG. 10A is a side view of a screen of a snow lantern according to an exemplary embodiment of the present invention;

FIG. 10B is a back view of a screen of a snow lantern according to an exemplary embodiment of the present invention;

FIG. 10C is a front view of a screen of a snow lantern according to an exemplary embodiment of the present invention;

FIG. 10D is a top view of a screen of a snow lantern according to an exemplary embodiment of the present invention; and

FIG. 10E is a bottom view of a screen of a snow lantern according to an exemplary embodiment of the present invention;

DETAILED DESCRIPTION

The present disclosure is generally related to an improved snow lantern that simulates falling snow in a realistic manner. To achieve this objective, according to an exemplary embodiment, a snow lantern includes a screen at a top portion of the lantern over which are blown particles fed from one or more tubes. The particles then fall through openings in the screen and cascade downward around the scene within the lantern in a uniform manner. In exemplary embodiments, the screen is arranged in a specific manner within the lantern and includes specific features that result in more effective dispersal of the particles.

FIG. 1 is a perspective view of a snow lantern, generally designed by reference number 1, according to an exemplary embodiment of the present invention. The snow lantern 1 includes a base portion 10, a display portion 20 and a cap portion 30.

The base portion 10 may include support elements, such as, for example, feet 12 that may be placed directly in contact with the ground.

The display portion 20 is disposed above and supported by the base portion 10. The display portion 20 includes a frame 22 that defines openings 24. Sheets 26 of transparent material are disposed within the openings 24 through which may be viewed a display scene (not shown) within the display portion 20. The transparent material may be, for example, plastic or glass. The openings 24 are illustrated as having a generally rectangular shape, but may have any other suitable shape, such as, for example, circular, square, or triangular, to name a few.

The cap portion 30 is disposed on top of the display portion 20. The cap portion 30 may include a ventilator 32 and a fixture loop 34. The fixture loop 34 may be used to hang the snow lantern 1 to a fixture, such as, for example, a post or a hook mounted on a wall.

FIG. 1 and FIGS. 2-5 show various views of the lantern 1 along with corresponding dimensions. However, it should be appreciated that the dimensions are not limited to those shown in the drawings, and the lantern 1 may have any other suitable dimensions.

FIG. 6 is a top view of the display portion 20 showing a top opening 25 of the display portion 20 and FIG. 7 is a bottom view of the display portion 20. Tubes 27a, 27b, 27c and 27d run vertically from the bottom to the top of the display portion 20. In an exemplary embodiment of the invention, at least a pair of the tubes 27a, 27b are in communication with blower pipes 40 (FIG. 7) through which are fed forced air from a blower (not shown) posi-

tioned in the base portion 10. The forced air sucks the particles simulating snow from the bottom of the display portion 20 into the blower pipes 40, and in turn into the pair of tubes 27a 27b in communication with the blower pipes 40. As described below, this construction allows the pair of tubes 27a, 27b to direct the particles to the top of the display portion 20, where the particles are then evenly distributed across the top opening 25 of the display portion 20 before falling back down over the display scene. In exemplary embodiments, the particles may be made of white-colored plastic.

The tubes 27c, 27d not used to direct the forced air may be used to house electrical wiring running from an internal or external power supply (not shown) into the display portion 20 to power lighting elements or other electrical elements of the display scene.

The tubes 27a, 27b, 27c, and 27d are preferably aligned with the frame 22 of the display portion 20 so that the tubes 27a, 27b, 27c, and 27d are at least partially hidden from view. For example, if the frame 22 is rectangular in shape, the tubes 27a, 27b, 27c, and 27d may be aligned with the frame elements at the four corners of the frame 22. As shown in FIGS. 8A and 8B, the tubes 27a, 27b, 27c, and 27d have a generally rectangular cross section, although it should be appreciated that the tubes 27a, 27b, 27c, and 27d may have any other cross-sectional shape, such as, for example, circular, square, or triangular, to name a few.

As shown in FIG. 9, a screen 50 is positioned on top of the display portion 20 to cover the top opening 25 of the display portion 20. FIG. 10A shows a side view of the screen 50, FIG. 10B shows a back view of the screen 50, FIG. 10C shows a front view of the screen 50, FIG. 10D shows a top view of the screen 50, and FIG. 10E shows a bottom view of the screen 50.

The screen 50 includes a number of screen openings 52. As explained in further detail below, the screen openings 52 are arrayed across the entire screen 50 so that particles blown out on top of the screen may fall through the screen openings 52 in an evenly distributed manner. In exemplary embodiments, the screen openings 52 are circular, and may include openings that are of all the same size or which vary in size from one another. In a specific exemplary embodiment, some of the screen openings 52 have a diameter of $\frac{5}{16}$ " and some of the screen openings 52 have a diameter of $\frac{1}{4}$ ". It should be appreciated that the screen openings 52 may have any other shape, such as, for example, rectangular, square or triangular, to name a few.

As shown in FIG. 10A, the screen 50 slopes downwardly from the back towards the front of the top opening 25 of the display portion 20. In exemplary embodiments, the angle of the slope may be in the range of 10° to 30° , preferably 15° to 25° , and in a preferred example, 20° .

As best seen in FIGS. 10B and 10C, the screen 50 has a profile that follows a convex curvature relative to the top opening 25 of the display portion 20. In an exemplary embodiment, the profile of the screen 50 is symmetrical with respect to a longitudinal axis of the display portion 20.

The screen 50 further includes tube connection openings 54a, 54b, 54c and 54d positioned to correspond with the top openings of the tubes 27a, 27b, 27c, and 27d. The tube connection openings 54a, 54b that correspond to the tubes 27a, 27b through which the particles are blown include fittings 56a, 56b that direct the particles inwards over the top of the screen 50. In exemplary embodiments, the fittings 56a, 56b direct the particles in a direction within a range of 80° to 100° , preferably 85° to 95° , and in a specific preferred example, 90° relative to the tube openings. In this regard, the

fitting **56** include an inside surface that follows a 130° curve inwardly towards the center of the screen **50**.

As shown in FIG. 10D, electrical wiring **60** passes through the tube connection openings **54c**, **54d** that correspond to the tubes **27c**, **27d** that house the electrical wiring.

In operation, particles simulating snow are blown upwards through the tubes **27a**, **27b**, and then exit through the fittings **56a**, **56b**. The angle of the fittings **56a**, **56b** directs the particles over the top surface of the screen **50**, and at least partially through action of gravity the particles fall through the screen openings **52**. The sloped and convex profile of the screen enhances the even distribution of the particles through the screen openings **52**, thereby providing a more realistic snowfall effect over the scene within the display portion **20**.

It should be appreciated that the present invention is not limited by application to a snow lantern. For example, a screen and corresponding tubes and fittings as described herein may be used in other products and structures, such as, for example, picture frames, aquariums, radios, cloches, gazebos, 360° scenes in glass formats, and wall frames, to name a few.

While particular embodiments of the present disclosure have been shown and described in detail, it would be obvious to those skilled in the art that various modifications and improvements thereon may be made without departing from the spirit and scope of the disclosure. It is therefore intended to cover all such modifications and improvements that are within the scope of this disclosure.

The invention claimed is:

1. A snow lantern comprising a display portion comprising a top opening, a front portion and a back portion; and a screen disposed over the top opening of the display portion and sloped downwardly from the back portion to the front portion, the screen comprising a plurality of screen openings through which pass particles for the simulation of falling snow within the display portion.

2. The snow lantern of claim **1**, further comprising: two or more first tubes through which the particles are blown upwards through the display portion and over a top surface of the screen.

3. The snow lantern of claim **2**, wherein the screen comprises two or more first tube connection openings in communication with the two or more first tubes.

4. The snow lantern of claim **3**, wherein the two or more first tube connection openings comprise fittings that direct the particles over the top surface of the screen.

5. The snow lantern of claim **4**, wherein the fittings direct the particles at an angle that is 80° to 100° relative to a longitudinal axis of the tubes.

6. The snow lantern of claim **4**, wherein the fittings direct the particles at an angle that is 90° relative to a longitudinal axis of the tubes.

7. The snow lantern of claim **3**, further comprising two or more second tubes that house electrical wiring.

8. The snow lantern of claim **7**, wherein the screen comprises two or more second tube connection openings in communication with the two or more second tubes.

9. The snow lantern of claim **1**, wherein the screen is sloped at an angle of 10° to 30°.

10. The snow lantern of claim **1**, wherein the screen is sloped at an angle of 20°.

11. The snow lantern of claim **1**, wherein the screen has a profile that is convex relative to the top opening of the display portion.

12. A snow lantern comprising a display portion comprising a top opening; a screen disposed over the top opening of the display portion, the screen comprising a plurality of screen openings; and

two or more first tubes through which particles are blown upwards through the display portion and over a top surface of the screen so that the particles pass through the screen openings for the simulation of falling snow within the display portion,

wherein:

the two or more first tube connection openings comprise fittings that direct the particles over the top surface of the screen at an angle that is 80° to 100° relative to a longitudinal axis of the tubes,

the display portion comprises a front portion and a back portion, and the screen is sloped downwardly at an angle of 10° to 30° from the back portion to the front portion, and

the screen has a profile that is convex relative to the top opening of the display portion.

13. A snow lantern comprising a display portion comprising a top opening; a screen disposed over the top opening of the display portion, the screen comprising a plurality of screen openings;

two or more first tubes through which particles are blown upwards through the display portion and over a top surface of the screen so that the particles pass through the screen openings for the simulation of falling snow within the display portion; and

two or more second tubes that house electrical wiring, wherein the screen comprises two or more first tube connection openings in communication with the two or more first tubes.
